UNITED STATES PATENT OFFICE.

CHARLEY S. SAVAGE, OF BURFIELD, KENTUCKY; J. C. HUFFAKER ADMINISTRATOR
OF SAID CHARLEY S. SAVAGE, DECEASED.

GATE.

1,102,691.

Specification of Letters Patent. Patented July 7, 1914.

Application filed July 28, 1913. Serial No. 781,618.

To all whom it may concern:

Be it known that I, CHARLEY S. SAVAGE, a citizen of the United States, residing at Burfield, in the county of Wayne and State 5 of Kentucky, have invented certain new and useful Improvements in Gates, of which the following is a specification, reference being had to the accompanying drawings.

This invention relates to new and useful 10 improvements in gates and more particularly to manually operated vertically swinging or tilting gates.

The object of the invention is the provision of a gate of the above character which 15 is particularly adapted for use upon country roads where the same crosses dividing fence lines and also along railroads where the public highway crosses the railroad.

Another object of the invention is the provision of a swinging gate which is provided 20 with suitable operating mechanism whereby by the gate may be opened and closed from a distance, thus persons nearing the gate in a vehicle may readily open the same, drive 25 through and then close the same from the opposite side without having to get out of the vehicle at all.

Another object of the invention is the provision of a gate of the above character 30 which will possess advantages in points of efficiency and durability, is inexpensive of manufacture and at the same time is simple in construction and operation.

With the above and other objects in view 35 this invention consists in the novel features of construction and the combination and arrangement of parts to be hereinafter more fully described, pointed out in the claims and shown in the accompanying 40 drawings, in which—

Figure 1 is a front elevation of a gate, parts being broken away and in section; Fig. 2 is a side elevation; Fig. 3 is a side elevation illustrating the gate in its open 45 position; Fig. 4 is a top plan view of the pivotal connecting member; Fig. 5 is an end elevation of one of the supporting posts at each side of the gate; Fig. 6 is a front elevation of the gate member; and Fig. 7 is a detail side elevation illustrating the manner of normally retaining the gate in a closed position.

Referring more particularly to the drawings, 1 indicates the elongated base member 55 of my improved gate which is supported at

each end thereof by means of the transverse beams 2. Mounted upon the forward end of the base 1 is a block 3 which is provided with the inner recess 4 and arranged within said recess at the ends thereof are the upright 60 posts 5 which are arranged in spaced relation and connected at their upper ends by means of a transverse piece 6. The posts 5 are arranged in spaced relation so as to receive the outer end of the swinging gate 7. 65

A reciprocating latch bar 8 is carried by the gate and normally held in its closed position by means of a coil spring 9, one end of which is connected to the latch bar and the other end connected to the upright end 70 post 10 of the gate. The outer end of the latch bar 8 is normally disposed beneath the transverse piece 6 so as to prevent any upward movement of the gate until the latch bar has been released. A second transverse 75 piece 11 is provided having a central recess 12 adapted to normally receive the outer end of the latch bar to prevent any lateral movement thereof.

Mounted upon the rear of the base 1 are 80 the two upright supporting posts 13 which are provided at their upper ends with the tapering offsets 14 forming suitable shoulders 15 upon which are adapted to rest the lower tapering ends of the diverging arms 85 16. The upper ends of the arms 16 are bifurcated to form the two spaced arms 17 between which are pivotally mounted by bolts 20 the operating levers 18. The upper ends of the arms 16 are suitably connected 90 by means of a transverse bar 19, the ends of which are mounted upon the pivot bolts 20. The rear end of the gate 7 is pivotally mounted at its lower end upon the pivot bolt 21 so that the entire upper portion of the 95 gate will be free to swing rearwardly between the two upright posts 13.

Mounted in the brace bars 22 of the gate is a transverse bolt 23 upon the ends of which are mounted the lower ends of the 100 spaced arms 24, the lower ends of said arms being enlarged, as shown at 25, and provided with the elongated slots 26 in which the ends of the bolt 23 are adapted to work. The enlarged portions 25 of the arms 24 105 are provided with beveled faces 27 which are adapted to work against the rollers 28 mounted upon the transverse bolt 29 which extends through the latch bar 8 adjacent the rear end thereof. From this it will be 110

seen that upon the upward movement of the arms 24, the beveled faces 27 will engage the rollers 28 and reciprocate the latch bar 8 to disengage the same from beneath 5 the transverse piece 6.

The upper ends of the arms 24 are pivotally mounted upon the lugs 29' extending from each end of the cross piece 30 which is secured to the forward end of the longitudinal bar 31. Secured to the rear end of the longitudinal bar 31 is a transverse pivoted bar 32, slightly longer in length than the cross piece 30 and is provided at each end with the lugs 33 which are pivotally mounted in the bearings 34 mounted upon the bracket 35. The longitudinal bar 31 is provided with a central recess 36 in which is arranged a transverse bolt 37 to which are pivotally connected the lower ends of the links 38, the upper ends of said links being movably connected to the eyes 39 carried by the inner ends of the operating levers 18. From this it will be seen that upon the downward movement of the outer 25 ends of the operating levers 18, the arms 24 will be actuated to swing the gate backwardly between the two upright posts 13, as clearly illustrated in dotted lines in Fig. 2.

30 Rigidly secured to the outwardly extending ends of the rear transverse beams 2 are the base supports 40 upon the outer ends of which are mounted the upright posts 41 having a transverse piece 42 mounted upon 35 and secured to the upper ends thereof, said posts being retained in an upright position by means of the brace members 43. The transverse piece 42 preferably extends inwardly toward the roadway and suspended 40 from the ends thereof are the pulleys 44 over which pass the operating cords 45 said cords passing upwardly and over the pulleys 46 suspended from the outer ends of the levers 18 and are secured to the eye 47 upon 45 the outer side of the diverging arms 16. A suitable hand hold 48 is secured to the lower end of each of the operating cords whereby the same may be readily grasped to actuate the operating levers 18 and open and close 50 the gate.

From the above description taken in connection with the accompanying drawings, it will be readily apparent that by pulling downwardly upon the outer ends of either 55 one of the operating cords 45, the levers 18 will be actuated pulling upwardly upon the arms 24, the upward movement of said arms engaging the beveled portions 27 with the rollers 28 to disengage the latch bar 8, further upward movement on the part of the 60 arms 24 swinging the gate upwardly and rearwardly between the two upright posts 13. It will be seen that after the vehicle has passed through the gate, the operating 65 cord upon the other side thereof may be ac-

tuated to return the gate to its normal closed position.

Mounted upon the outer end of the longitudinal bar 31 and the cross piece 30 is a suitable receptacle 49 which is adapted to contain stone or other suitable material to provide a weight to normally retain the gate in a closed position and to assist in moving the same to its open or closed position. 70

From the above it will be seen that I have provided a simple and practical gate of the character described which is particularly adapted for use upon country roads, passage of which is interrupted by crossing fences and also along the railroads. 75

It will be apparent from the above that my device can be manufactured and placed in use at very small cost. 80

While I have shown and described the preferred form of my invention, it will be obvious that various changes in the details of construction and in the proportions may be resorted to for successfully carrying my invention into practice without sacrificing any of the novel features or departing from the scope of the appended claims. 90

What I claim is:

1. A device of the class described including a base, spaced upright posts mounted thereon, a gate mounted for swinging movement so that the entire gate will swing between the posts, a latch bar normally retaining the gate in its closed position, rollers disposed upon opposite sides of the gate and secured to the latch bar, movable arms arranged upon opposite sides of the gate and loosely connected thereto, means for actuating said arms to open the gate, said arms engaging the rollers carried by the latch bar to release the gate from its locked position. 95

2. A device of the class described including a base, spaced upright posts mounted thereon, a gate mounted for swinging movement between said posts, a latch bar carried by the gate to normally lock the same in its closed position, rollers carried by the latch bar and arranged upon opposite sides thereof, a transverse bolt carried by the gate, movable arms having slots in their lower ends to receive the ends of said bolt, beveled portions formed on said arms and engaging the rollers on the latch bar, means for actuating said arms to release the latch bar and impart movement to the gate to swing the same between said posts. 100

3. A device of the class described including a base, spaced upright posts thereon, a gate mounted for swinging movement between said posts, a latch bar normally retaining the same into locked position, rollers carried by said latch bar, brackets secured to said posts adjacent the upper end thereof, a transverse bar pivotally mounted therein, a longitudinal bar secured to the same and extending between said posts, a 105

second transverse longitudinal bar secured to the opposite end of the first bar, spaced arms having their upper ends pivotally connected to the ends of the second transverse bar and having slots formed in their lower ends, beveled portions formed on said arms and adapted to engage said rollers, a transverse bolt carried by the gate and having its ends arranged in said slots, and means for raising and lowering the longitudinal bar for actuating said arms to release the latch bar and impart movement to the gate to swing the same between said posts.

4. A device of the class described including spaced upright posts, a gate having one end arranged between the post and pivotally mounted at its lower side for swinging movement between the posts, a resiliently re-

tained latch bar normally holding the gate in its locked position, a frame arranged 20 between said posts and mounted at one end for pivotal movement, movable arms having one end pivotally connected to the other end of the frame, and the opposite ends of said arms being loosely connected to the 25 gate, means for imparting movement to said frame to actuate the gate and means carried by the latch bar and engaged by said arms to release said latch bar.

In testimony whereof I hereunto affix my 30 signature in the presence of two witnesses.

CHARLEY S. SAVAGE.
